UNITED STATES PATENT OFFICE.

HAROLD L. BLANCHARD, OF MILLBURY, MASSACHUSETTS, ASSIGNOR TO CROMPTON & KNOWLES LOOM WORKS, OF WORCESTER, MASSACHUSETTS, A CORPORATION OF MASSACHUSETTS.

TRANSFER MECHANISM FOR WEFT-REPLENISHING LOOMS.

Application filed September 21, 1925. Serial No. 57,512.

This invention relates to transfer mechanism for weft replenishing looms and more particularly to a yieldable device which will prevent breakage should the bobbin about 5 to be transferred be improperly placed. In weft replenishing mechanism of the multi-color type the bobbins to be transferred are ordinarily arranged in vertical parallel stacks from which they are delivered to a common transfer position. Due to faulty release or an oversized bobbin the latter will occasionally be disposed diagonally with respect to the axis of the shuttle, and will not be moved into the shuttle properly by the 15 transferrer arm.

Transferrer arms as at present used comprise a pair of spaced depending fingers for the lay engaging latch and a horizontally disposed arm which engages the incoming 20 shuttle to move the same downwardly, the whole being integral. After the transferrer arm is connected with the lay, it is required to move downwardly thereby and should a bobbin be misplaced, breakage will result 25 either in the magazine or shuttle. It is the general object of my present invention to prevent the aforesaid breakage by providing a yielding connection between the lay and the bobbin to be transferred.

In multi-color weft replenishing mechanism the weft detector is usually on the replenishing end to cooperate with the single box and it is necessary to withdraw the detector on faulty as well as proper transfer 35 ring picks. With yielding transferrer arms as proposed heretofore no provision has been made for the withdrawal of the detector, the same remaining unchanged and in position to be damaged by the incoming bobbin. It 40 is accordingly a further object of my invention to provide a yieldable transferrer arm having a feeler withdrawing part which performs its normal feeler withdrawing function even though the arm yields to prevent 45 breakage.

The usual form of transferrer arm is held in raised position by a coil spring, one end of which is anchored on a fixed stud and the other end of which engages some portion of 50 the transferrer arm. It is a more particular object of my invention to provide a transferrer arm formed of relatively movable

parts and employ the resilience of the coil spring to resist relative angular movement of the component parts.

It is a still further object of my invention to provide a transferrer arm the hub portions of which are spring pressed together to be relatively movable longitudinally of each other and so arranged that the portion which engages the usual spring will be moved towards the latter at the time of an improper transfer to insure continued contact with the spring. In this connection I form the two hub members of the transferrer arm with interengaging teeth which permit yielding movement in one direction against the normal spring, but which require the horizontal arm to move to normal raised position when the coil spring is free to act on the depending fingers.

With these and other objects in view which will appear as the description proceeds, my invention resides in the combination and arrangement of parts hereinafter described and set forth in the claims.

In the accompanying drawings, wherein I have shown a convenient embodiment of my invention.

Fig. 1 is an end elevation of a portion of a multi-color weft replenishing mechanism, looking from the central portion of the loom and having my improved transferrer arm shown in normal position.

Fig. 2 is a view similar to Fig. 1, but showing the transferrer arm in a yielding position as it engages an improperly positioned bobbin.

Fig. 3 is a front elevation taken in the direction of arrow 3, Fig. 1.

Fig. 4 is an enlarged vertical longitudinal section through the transferrer arm hub.

Fig. 5 is an enlarged fragmentary view looking in the direction of arrow 5, Fig. 3, showing the two portions of the transferrer arm hub in separated relation, and

Fig. 6 is a vertical transverse section, taken on line 6—6 of Fig. 5.

Referring to the drawings it will be seen that I have provided a weft replenishing mechanism 10 of the usual multi-color type, having a fixed stud 11 secured therein by set screw 12, as shown in Fig. 3. The transferrer mechanism comprises a substantially

horizontal arm 13 having a bobbin engaging foot 14 movable vertically through a slot 15 formed in the replenishing mechanism. Said arm 13 is provided with a horizontally extending hub 16 integral therewith and movable freely about the stud 11. Said hub 16 has a reduced section 17 and a still further reduced end portion 18 around which is located a coil spring 19. The end of the stud 11 is turned down as at 20 and has mounted thereon a collar 21 held to the stud by a pin 22. One end of the coil spring is received by the collar as at 23 and the other end thereof engages one of the depending fingers to be described hereinafter. The matter thus far described is of the usual form and with the exception of the reduced portion 17 of the hub 16 forms no part of my present invention.

20 In carrying out my invention I provide a sleeve 30 normally held fixed with respect to the hub 16 and having depending therefrom a pair of substantially parallel spaced fingers 31. The hub 16 is provided with 25 teeth 32 and notches 33, while the sleeve 30 is provided with corresponding teeth 34 and notches 35. Said notches and teeth are normally engaged with each other as shown in Figure 3 and are held in this position by 30 a heavy compression coil spring 36 disposed between nuts 37 threaded on the reduced section 17 of the hub 16 and the adjacent end of the sleeve 30, said spring serving to move the sleeve 30 to the left as shown in 35 Fig. 3. The pressure of the spring is adjustable by means of the nuts 37.

Extending between the fingers 31 is a stud 38 upon which is pivoted for free movement a latch 39 having a notch 40 adapted 40 to engage a bunter 41 forming part of the box plate 42 mounted on the lay 43. Said latch is raised by means of a connector 44 operatively attached to the upper part of the weft replenishing mechanism and is 45 raised at the time of transfer from the position shown in Fig. 1 to that shown in Fig. 2. The free end 45 of coil spring 19 engages one of the fingers 31 to hold the transfrerer arm in its normal raised position 50 and also to move the fingers 31 rearwardly with respect to the hub 16 when the parts of the arm are displaced from normal relative position.

The weft detector comprises a stand 46 55 held in fixed position and having mounted therein for vertical movement a block 47 on which is pivoted an actuator lever 48. One end of this lever is connected by a rod 49 to the replenishing mechanism not shown and the other end thereof moves in a slotted arm 50 through which extends a controller pin 51. The latter is operatively connected by well known means to the yarn engaging detector 52 carried on a slide 53 mounted in 60 a feeler bed 54 supported on the stand 46.

A lug 55 is secured to the slide and is positioned for engagement by the extended end of stud 38 movable with the fingers 31.

Under normal conditions, at the time of transfer, the latch 40 will be raised to the 70 position shown in Fig. 2, where it will be engaged by the bunter 41 and moved forward as the lay advances and stud 38 will engage the lug 55 to withdraw the detector out of the path of the incoming bobbin. 75 Should the incoming bobbin be properly positioned with respect to the shuttle it will be engaged by the foot 14 of the transfrerer arm 13 and inserted in the shuttle the 80 springs 19 and 36 holding the parts of the arm together so that they move as a unit. Should the bobbin be improperly positioned, however, as indicated in Fig. 2, so as to have the axis thereof oblique with respect to the shuttle, it will not move into the 85 shuttle properly and will prevent downward movement of the transfrerer arm 13. As the advancing lay continues to move the fingers 31 forward the sleeve 30 will rotate about the hub portion 17 and cause teeth 34 90 to move along the adjacent faces of the teeth 32 formed on the hub 16 against the action of springs 19 and 36. The parts will then assume the position shown in Fig. 2, 95 wherein it will be seen that the arm 13 is permitted to remain in raised position without resultant damage either to the bobbin, shuttle or adjacent portions of the replenishing mechanism and that the latch 40 is permitted to move forward under action of 100 the bunter 41 as the lay approaches front center to withdraw the feeler. As the lay recedes the pressure of the springs 19 and 36 will return sleeve 30 to its normal position 105 as shown in Fig. 3 through the action of 110 the teeth and notches.

From the foregoing it will be noted that the separating movement of the sleeve 30 with respect to the teeth formed on the hub 16 is toward the spring 19 so that continued 115 cooperation of the said spring and fingers 31 is insured. It will also be noted that the tendency of spring 19 is to return the sleeve 30 to its normal relative position with respect to the hub 16 when said parts are separated. Furthermore, it will be noted that the weft detector is withdrawn on all the 120 transferring picks, whether the transfer be proper or faulty.

Having thus described my invention it 125 will be apparent that changes and modifications may be made therein by those skilled in the art without departing from the spirit and scope of the invention, and I do not wish to be limited to the details herein disclosed, but what I claim is:

1. In a transfer mechanism for weft replenishing looms, a transfrerer arm, a hub integral therewith, a stud mounted in fixed position for the hub, teeth formed on the 130

hub, a sleeve surrounding a portion of the hub, teeth formed on the sleeve, resilient means to hold the teeth in operative engagement with each other, a lay engaging member supported by said fingers, and a coil spring surrounding a portion of the hub and having one end thereof in engagement with one of the fingers of the sleeve and having the other end thereof held in fixed position 10 with respect to the stud, said sleeve being movable longitudinally with respect to the hub at the time of improper transfer toward said coil spring.

2. In a transfer mechanism for weft re-
15 plenishing looms, a transerrer arm, a hub integral therewith, teeth formed on said hub and having surfaces inclined with respect thereto, a sleeve mounted on said hub,

fingers depending from the sleeve, a lay-engaging member supported by the fingers, 20 teeth formed on said sleeve and having inclined surfaces to engage the teeth formed on the hub, resilient means of holding said teeth in operative contact with each other, and a coil spring having one end held in fixed position and having the other end thereof in normal contact with one of the depending fingers to hold the transerrer arm in raised position but permitting yielding relative angular movement of the sleeve 25 in respect to the hub at the time of improper transfer.

In testimony whereof I have hereunto affixed my signature.

HAROLD L. BLANCHARD.
